IMPACT BOLL BREAKER

Filed March 21, 1931

INVENTOR:
JOHN E. MITCHELL

By Bruce J. Elliott

ATTORNEY.

UNITED STATES PATENT OFFICE

JOHN E. MITCHELL, OF DALLAS, TEXAS

IMPACT BOLL BREAKER

Application filed March 21, 1931. Serial No. 524,237.

The general object of this invention is to provide novel apparatus, for breaking and opening bolls, the apparatus employed being located in the cotton-elevating conduit of a gin, which operates by suction induced therein to withdraw cotton from a suitable source of supply, such as a cotton-house, or wagons being unloaded, and to deliver to a distributor, which, in turn, delivers the cotton to the respective feeding mechanisms of a line of cotton cleaning and ginning machinery below.

It has heretofore been customary to use a combination boll breaking and cleaning machine above the distributor, not only for the purpose of partially cleaning the cotton, but chiefly for opening the bolls to free enough of the cotton to permit uniform feeding to the cleaning machinery located below the feeding mechanism. All such machines are provided with a metal breaking shoe co-operating with spikes or bars on a rotating cylinder, the bolls being caught between the hard surfaces and crushed.

The chief objection to this boll crushing mechanism is that the grinding or crushing action resulting from forcing the bolls between the spikes or bars of the rotating cylinder and those on the stationary breaking shoe, results in considerable shale being loosened and the hulls broken into small pieces, the amount of the trash caused by the action depending upon the character of the cotton, being greater, of course, when the bolls are very dry or brittle.

It is also obvious that when the concave or stationary shoe is set close enough to the rotating cylinder to catch the small bolls, the crushing action is especially severe on the larger ones.

To avoid the crushing or grinding action on the bolls, which is unavoidable with the boll breakers heretofore used, my invention involves the use of a high speed impact wheel mounted to rotate in the air line, or conduit, through which the cotton is elevated from the source of supply, the bolls being broken or opened by impact of the blades of the wheel therewith, and of the bolls with the wall of the housing of the wheel, and such action

occurring without any substantial interruption of the passage of the seed cotton and bolls through the conduit.

It should be stated that I find it desirable to use such boll breaking means prior to the distribution of the mixed cotton and bolls to the cleaning machines, not because the boll breaking cylinders of these machines do not break the bolls, but because the bolls do not reach the cylinder until after they pass through the feeding mechanism from the distributing conduit, and when tight or closed bolls are handled, they do not feed uniformly. That is, they do not bridge properly across the space between the two conventional feeding rolls of the cleaning machines; whereas when a sufficient number of the bolls are opened to free enough of the cotton to increase the bulk, the mass will bridge across the space between the feeding rolls in a way that permits a more uniform supply or feed to the cleaning or ginning machinery below.

The invention is illustrated in the accompanying drawing, in which the view illustrates, partly in section, and partly in elevation, an elevating conduit having my improved impact boll breaker and opener mounted therein.

Referring to this drawing, the numeral 1 indicates a circular conduit having a pipe 2 connected to one end thereof by means of a flexible joint 3, and through which pipe and conduit suction is adapted to be set up by means of a suction fan 4 suitably associated therewith, as hereinafter explained. Rotatably mounted at a suitable point in the length of the conduit is my improved impact wheel 5, having radial blades 6. The impact wheel may be constructed in various ways, but as shown it is formed of strips of metal connected together to form a rectangular body portion 7 with the blades 5 located at each corner thereof, the said body portion and blades extending between and being connected to circular end plates 8. The impact wheel is substantially the width of conduit 1, and has a shaft 9 provided on one end with a pulley 10 by means of which it may be rotated at a relatively high speed by means of a belt 11. The conduit 1 is provided on its

bottom side with a circular enlargement 12 which is located in close proximity to the lower half of the impact wheel, and on its upper side is provided with a larger circular enlargement, or housing, 13, concentric with the periphery of the impact wheel, but located at a distance therefrom so as to provide a circular path 14 for the passage of the current of air around the upper half 10 of the impact wheel. The shaft 9 of the impact wheel is mounted in suitable bearings at opposite sides of the conduit 1, and the impact wheel is so positioned in the conduit that the lower side, 15, of the conduit, extending in right lines beyond opposite sides of the impact wheel, is substantially in the plane of the axis of the latter.

In order to separate the air from the cotton drawn through the conduit 1, there is provided between the impact wheel 5 and the exhaust fan 4 a casing 16, with which the conduit 1 communicates at one side and in its upper portion. An air duct 17 extends from the suction side of the fan 4 to the opposite side of the casing 16, and communicates therewith at its lower end. Located within the casing 16 is a curved screen 18, the upper end of which is connected with the inner wall 20 of the casing 16, and its lower end to one side of a housing 19, open at its top and bottom, and in which is mounted a flutter wheel 20, rotating in air tight connection with the opposite side walls of the housing 19, and operating to discharge cotton from the casing while preventing the admission of air through said housing into the casing.

The casing 16, with its screen and feed wheel, mounted in the air line as described, constitutes a conventional exhauster, or separator; that is, it provides a means for separating the air from the cotton.

Feed wheel 20 has a shaft 21 suitably journaled in opposite sides of casing 16, on one end of which is provided a pulley 22, by means of which it is driven from a belt 23, and a pulley 24, for receiving belt 11, which drives the impact wheel 5. The exhaust fan is driven by means of a belt 25, the belts 23 and 25 being in turn driven from a suitable source of power, not shown.

While it is impossible to illustrate the velocities of the bolls and air current through the conduit 1 with relation to each other and to the surface speed of rotation of the impact wheel 5, except as this may be roughly indicated by the relative sizes of the various driving and driven pulleys involved, it is essential, to secure the best results from my invention, that the blades 6 of the impact wheel 5 at their outer ends should move at a speed considerably greater than the velocity of the bolls carried through the conduit with the air current, and greater than the velocity 65 of the air current.

The device described being in operation, and the lower end of the housing 19 being understood to be located over the inlet to a distributor, which conveys the seed cotton over the inlets to a line of cotton cleaning machines, the lower end of the pipe 2 is moved into engagement with the cotton in the wagon, cotton-house, or other source of supply, and such cotton is drawn by suction of fan 4 into and through conduit 1. When the boll cotton reaches the horizontal part of the conduit leading into the housing of the impact wheel, the bolls, either closed or partly opened, being, of course, heavier than the cotton will slide along the bottom 15 of the conduit, so that as the air current changes its direction around and over the impact wheel, the bolls are directed toward the axis of the wheel and are inevitably caught by the blades in the upper half of their revolution and thrown across the air current in the space 14. The speed at which the impact wheel revolves causes the bolls to be thrown with great force against the wall of the enlargement 13, and due to the impact of the blades of the wheel with the bolls and, possibly, to a greater extent, of the impact of the bolls with the wall of said enlargement, the bolls will be broken open to free the cotton, and this occurs without shaling or breaking the hulls, and the work is performed in a very small space and with the expenditure of very little power, this latter result being due to the fact that the bolls are acted upon while in a state of motion, and unconfined, and no crushing or grinding action is exerted on them. Further, there is no difference in the breaking action as between large bolls and small bolls. The stream of opened bolls on leaving the housing of the impact wheel, goes with the air to the separator. The air passing through the screen 18 goes to the exhaust fan 4, while the cotton and hulls are discharged from the separator by the wheel 20.

In the operation of my apparatus, it will be seen that the bolls are opened by the force of impact, within an air line or conduit through which the cotton is elevated, and that this is done without any interruption to the continuous movement through the conduit of the boll cotton drawn into the conduit from the source of supply. To accomplish the above, the impact wheel, which is made substantially the same width as the conduit, rotates at a speed that will move the tips of the blades forward in the induced air current more rapidly than the current moves through the conduit under the action of the exhaust fan. In other words, the construction and operation of the device is such that a stream of bolls will pass through the circular space 14 around the impact wheel almost, if not fully, as fast as it would move the same distance in a straight line if the 130

wheel were not interposed in the length of the conduit. This speed of movement, or continuity of action, within the air line is essential by reason of the large amount of 5 bolls that must be handled within a given time. That is to say, the cotton for the entire ginning capacity of the plant must pass through conduit 1, and it is obvious that any hindrance to the free movement of the 10 boll cotton through the conduit would not only reduce capacity, but would soon clog up the conduit. This latter result would occur if the tip speed of the impact wheel were less than the air velocity, or were not greater 15 than the velocity of the bolls carried through the conduit by the air current.

From the above, it will be readily seen that the construction is such that the bolls while being drawn through the conduit in a straight 20 line will necessarily be directed into contact with the blades of the impact wheel; there are no expansion chambers, such as are usually employed, or other enlargement of the conduit, that would cause a portion of the 25 stream to settle or accumulate; there are no obstructions in, or constrictions of the conduit or housing that would materially interfere with the free, rapid movement of the in-

duced air current carrying the bolls through the conduit; and the bolls opened by the force of the impact with the blades therewith, or by impact of the bolls with the wall of the enlargement 14, will not be appreciably 70 checked or retarded in their movement through the conduit.

I claim:—

In combination with a rotary impact member, a conduit extended at an angle therefrom 75 with its bottom substantially in the plane of the axis of the rotary member, a housing forming a circular continuation of the conduit around the upper portion of said rotary member, and means for drawing boll cotton 80 through the conduit by an induced air current, whereby the change in direction of the air current from the extended to the circular portion of the conduit will cause the bolls to be directed from said extended portion 85 into contact with the rotating impact member and thrown by same forward across the air current into contact with the outer wall of the circular conduit.

In testimony whereof, I have hereunto set 90 my hand.

JOHN E. MITCHELL.
